UNITED STATES PATENT OFFICE.

JOHN M. BANKER, OF SAGINAW, MICHIGAN.

DESIGN FOR A BADGE.

SPECIFICATION forming part of Design No. 25,543, dated May 26, 1896.

Application filed February 21, 1896. Serial No. 580,263. Term of patent 7 years.

To all whom it may concern:

Be it known that I, JOHN M. BANKER, a citizen of the United States, residing at Saginaw, county of Saginaw, and State of Michigan, 5 have invented and produced a new and original Design for a Badge, of which the following is a specification, reference being had to the accompanying drawing, showing a part thereof.

10 The figure is a face view of my design, this view being deemed necessary to fully illustrate my design.

15 The leading features of my design consist in the tri-pointed star-shaped figure having its conical points A A A radiating from the sides of the triangular-shaped figure B B B, the outlines of the conical points and of the triangle containing symbolic representations,

as hereinafter set forth, the whole uniting to form a design for a badge, as shown in the illustration. The outlines of each conical point A A A inclose one of the three symbolic representations—viz., the trumpet *a*, the sheaf *b*, and the crown and scepter *c*, in connection with the design for a badge, as shown in the 25 illustration. The triangular outlines B B B inclose the representation of an open Bible, in connection with the design for a badge, as shown in the illustration.

What I claim is—

30 The design for a badge as herein shown and described.

JOHN M. BANKER.
